UNITED STATES PATENT OFFICE.

LEWIS AIRHART, OF WEST READING, PENNSYLVANIA, ASSIGNOR TO TEXTILE MACHINE WORKS, OF WYOMISSING, PENNSYLVANIA, A CORPORATION OF PENNSYLVANIA.

ELECTRICALLY-HEATED STAMPING-PRESS.

1,099,892.

Specification of Letters Patent.

Patented June 9, 1914.

Application filed December 3, 1913. Serial No. 804,341.

To all whom it may concern:

Be it known that I, LEWIS AIRHART, a citizen of the United States, residing at West Reading, in the county of Berks and State of Pennsylvania, have invented certain new and useful Improvements in Electrically-Heated Stamping-Presses, of which the following is a specification.

My invention relates to that class of stamping machines in which a reciprocatively mounted die or presser plate is employed in connection with means for electrically heating the latter; and it consists in an improved construction in which a self-contained means for regulating the electric heating is conveniently embodied, as fully described in connection with the accompanying drawings and specifically pointed out in the claims.

Figure 1 is a partly sectional elevation of a mechanism embodying my invention. Fig. 2 is a cross-sectional view on the line 2—2 of Fig. 1.

My improved mechanism comprises a supporting frame or standard 2, which may be fixed to any convenient table 3, and a flexible conductor 4 conveniently attachable by means of a socket 5 to any incandescent circuit in place of an ordinary lamp; and any required regulation of the current for securing a proper heating of the movable presser plate or die 6 is provided for by self-contained means so that the mechanism may be conveniently employed independently of any fixed provision for such regulation.

In the vertical frame 2 is mounted a cross-head 10, having a lateral projection 11 which is engaged in a guide-way 12 of the frame, and a fixed vertical guide-rod 13 extending both above and below said cross-head through aligned guide apertures 14 and 15 at the top and bottom of the frame; reciprocating movement being imparted thereto, as indicated, by means of a treadle 16 and a spring 17. To this cross-head is fixed a horizontal carrier arm 20, having at its outer end a fixed vertical holder 21 with the die or presser plate 6 adjustably fixed to the reduced lower end.

The die holder 21 is preferably formed of

copper or like material, and is inclosed by an electric heating coil 25, which is preferably wound upon a layer of mica and covered by a layer of asbestos, while the convolutions of the coil are suitably insulated as by silicate of soda and the ends thereof are connected respectively to wires 29 and 30 through rings 31 and 32, so that the passage of an electric current will heat the die 6.

The carrier arm 20 is inclosed by a similarly insulated coil 35; the covering of asbestos however being omitted on the latter, and one end thereof being connected at 36 with wire 29 extending to the heating coil 25, while a conductor ring 37 adjustably slidably thereon is connected to a wire 38 joining with the wire 30 to form the flexible conductor 4 to the source of electricity. The construction described thus provides a self-contained adjustable resistance, through which more or less of the current is conveyed to the heating coil 25 as determined by the conditions of operation.

The flexible conductor 4 is fixedly connected to the top of the cross-head guide rod 13, so that the wires 30 and 38 are maintained in fixed relation to the carrier arm 20 and die holder 21 during operation of the machine; and said conductor 4 provides the only attachment required for operation of the machine, convenient adjustment of the conductor ring 37 upon the resistance coil 35 varying the heat imparted to the die plate 6 as desired.

What I claim is:

1. In combination with a vertical supporting frame, a vertical die-holder having a horizontal carrier arm reciprocatively guided in said frame, a heating coil on said die-holder, a resistance coil on said carrier arm, a regulator adjustable upon said resistance coil, and electric connections to said heating and resistance coils substantially as and for the purpose set forth.

2. In combination with a supporting frame having guide-ways, a reciprocating cross-head having a fixed vertical rod and a lateral projection respectively engaged in said guide-ways, a horizontal carrier arm rigidly fixed to said cross-head, a die-holder verti-

cally fixed to the free end of said carrier arm, resistance and heating coils on said carrier arm and die-holder arm respectively, and electric connections to said coils attached 5 to the projecting upper end of said vertical guide-rod, substantially as and for the purpose set forth.

In testimony whereof I affix my signature in presence of two witnesses.

LEWIS AIRHART.
